UNITED STATES PATENT OFFICE.

ALEXANDER E. BLOCK, OF ST. LOUIS, MISSOURI.

FOOT-SUPPORT.

1,243,692.

Specification of Letters Patent. Patented Oct. 23, 1917.

Application filed December 9, 1912. Serial No. 735,803.

To all whom it may concern:

Be it known that I, ALEXANDER E. BLOCK, a citizen of the United States, and a resident of St. Louis, Missouri, have invented 5 certain new and useful Improvements in Foot-Supports, of which the following is a specification.

My invention relates to foot supports, and has for its object to provide a fixed or 10 movable insole with elevating means for the support or treatment of the heel, the longitudinal arches, or the posterior transverse arch, of the human foot.

In the drawings—

15 Figure 1 is a plan view of the foot support of my present invention, portions being broken away.

Fig. 2 is a longitudinal sectional view of the same, taken on the line 2—2 of Fig. 1.

20 Fig. 3 is a side elevation of the same.

Fig. 4 is a transverse vertical sectional view of the same taken on the line 4—4 of Fig. 3.

25 Fig. 5 is a similar view taken on line 5—5 of Fig. 3.

While my invention may be practised by the attachment of the various parts, illustrated in the drawings and to be described herein, upon a fixed insole, I have illustrated 30 them in connection with a removable insole 1, upon the lower face of which the sheet 2 is secured by any desired means. To equip the support with means for elevating the heel of the wearer at a point beneath the 35 lower extremities of the heel bone (the tuberosities of the os calcis) I provide a heel-bone-support 4, removably mounted in the pocket formed by the attachment of the flexible layer 3 (see Figs. 1, 2 and 4). The

40 size and relative dimension of the heel-bone-support 4 have considerable latitude, dependent upon the size of the foot, and the object which is to be attained by the use of said support 4. For example; in shoe manufacture that portion of the insole which surrounds the heel of the shoe is more or less concave, and may or may not fit the heel of the foot of the wearer. When the heel bone of the wearer is inconvenienced by an 45 excessive concavity of the insole, my invention counteracts the concavity by building up the insole at that point by means of the support 4. Similarly, in the use of heel supports, extending across the width of the insole, and constructed of rubber, felt, cork,

curled hair of papier-mâché, such supports if use pack down, and lose their resiliency, and are decreased in thickness at their central point beneath the heel bone; and my invention is designed to counteract such depression and to renew the resiliency of said supports so impaired by wear, which it accomplishes by the heel-bone-support 4.

In that form of my invention illustrated in the drawings, a layer of sheet material 5 is secured to the sheet 2 to form a pocket open at the rear end of the insole, having its front edge secured transversely across the insole, and its side edges secured for the front portions of their lengths at the outer margins of the insole 1; the pocket so formed being adapted to receive the insert 7, which will be of such varying thickness throughout its width and length as may be indicated by a diagnosis of the foot for whose treatment it is to be used. I have illustrated a like layer of sheet material 6, secured in like manner to the sheet 2, to form a pocket for the reception of the insert 6, such pocket being longer than the one receiving the insert 7, the said pockets being superimposed, the longer overlapping the shorter. Said pockets are secured to the insole 1 by the transverse line of stitching 10 and marginal lines of stitching 11 and 12.

The insert 8, as illustrated in the drawings, is of such length that its front portion may be used in the treatment of the posterior transverse arch of the foot, and I have illustrated in Fig. 5, the manner in which its thickness may be made greater at one side or the other of its front end, as the treatment of said transverse arch may require.

The number of the pockets may be increased without departing from my invention, their number and length being determined by the particular abnormality of the foot which is to be treated; in cases where treatment is instituted when the foot 100 is in swollen condition, the inserts will be lessened in number, or decreased in thickness as the swelling subsides. The heel-bone-support 4 may be used in connection with, or independently of any one or more 105 of the other inserts above described. The pockets may be apertured to receive the inserts along any desired line of sufficient width to admit the inserts.

Having thus described my invention, what 110

I claim as new and desire to have secured to me by the grant of Letters Patent, is—

1. In a foot support the combination of an insole; a heel-bone-support; means for removably positioning said heel-bone-support relatively to the insole at a point beneath the heel bone of the wearer; a layer of sheet material secured to a face of the insole to form a pocket open at the rear end of the insole, having its side edges secured for a portion of their length at the outer margin of the insole; and an insert adapted to be mounted within said pocket.
2. In a foot support, an insole; a heel-bone-support; means for removably positioning said heel-bone-support relatively to the insole at a point beneath the heel-bone of the wearer; a plurality of inserts; and a series of layers of sheet material secured to a face of the insole and superimposed upon and overlapping each other to form a series of pockets, and apertured at the rear of the insole to receive said inserts.
3. In a foot support, an insole; a heel-bone-support; means for removably positioning said heel-bone-support relatively to the insole at a point beneath the heel bone of the wearer; a plurality of inserts; and a series of layers of sheet material secured to a face of the insole and superimposed upon and over-lapping each other to form a series of pockets apertured to receive said inserts; said pockets being of various lengths and
- extending from the rear margin of the insole to various points beneath and beyond the line of the transverse arch of the foot of the wearer.
4. In a foot support, an insole; a heel-bone-support; means for securing said heel-bone-support relatively to the insole at a point beneath the heel-bone of the wearer; a plurality of inserts; and a series of layers of sheet material secured to the lower face of the insole and superimposed upon and overlapping each other to form a series of pockets of different lengths located in the heel of the insole and apertured to receive said inserts.
5. In a foot support, an insole; a heel-bone-support; means for securing said heel-bone-support relatively to the insole at a point beneath the heel-bone of the wearer; a plurality of inserts; and a series of layers of sheet material secured to the lower face of the insole by one transverse and two marginal lines of stitching and superimposed upon and overlapping each other to form a series of pockets of different lengths, apertured at the rear of the insole to receive said inserts.

In testimony whereof, I have signed my name to this specification, in presence of two subscribing witnesses.

ALEXANDER E. BLOCK.
